INVENTOR
Richard Remmler
BY
Peter M. Boesel, Jr.
ATTORNEY

UNITED STATES PATENT OFFICE.

RICHARD REMMLER, OF NEW YORK, N. Y.

WATCH-PROTECTING CASE.

Application filed April 3, 1925. Serial No. 20,341.

To all whom it may concern:

Be it known that I, RICHARD REMMLER, a citizen of the Republic of Germany, whose residence is 167 E. 108th Street, New York city, county and State of New York, have invented certain new and useful Improvements in Watch-Protecting Cases, of which the following is a specification.

This invention relates to improvements in means for securing and keeping a watch in the pocket and has for its object to provide a case of inexpensive construction, which is more practical than any of the kind heretofore known and now commonly used.

Another object of the invention is to provide a case which, being detachably secured to the pocket, will prevent the watch from falling out during exercises and golf playing, and which will prove an obstacle to pickpocketing, while at the same time the watch by means of the special construction of the case will be easily accessible to the wearer.

With the above and other objects in view, the invention consists of the novel features of construction, combination and arrangement of parts hereinafter fully described and claimed, and illustrated in the accompanying drawings, in which:

Figure 1 is a front elevation of a watch protecting case; Fig. 2 is a vertical section on the line *a—a* of Fig. 1; Fig. 3 is a transverse sectional view on the line *b—b* of Fig. 4; Fig. 4 is an edge view, and Fig. 5 represents a perspective detail view of a foundation bar, supporting said watch protecting case.

Corresponding and like parts are referred to in the following description, and indicated in all views of the drawing by the same reference characters.

Referring in detail to the drawing, this invention comprises a foundation bar 10, having two projections 11, to which are pivotally hinged, as shown at 12, two half sectional cases C, C. Two pivotal pins, 19, resting in openings 22 in said projections, securing the case parts together. These two case parts have at their lower ends extending past the hinging point each a projection formed into a hook 13, between which a preferably coiled spring 14 is detachably secured; this spring has for its purpose, when in relaxed position, to keep the two case parts closed or locked together, as shown in Fig. 1. The case parts, C and C, are symmetrical with the watch, which they

when closed will embrace. For the purpose of protecting the watch from scratches and abrasions said case parts may be lined inside with leather, velvet, or the like.

Each case part has on the corresponding side a half-circular opening 15 for displaying the index-hands of a watch, and the surface of said case parts is provided with numerals to correspond with the dial of a watch, as shown in Fig. 1.

While the two case parts joined together form a snug and tight fitting enclosure, each part is at the top provided with a projection or knob 16.

When it is desired to open the protecting case the knobs 16 are manipulated by the fingers to a distance sufficiently apart from each other to permit the removal of the enclosed watch.

The foundation bar 10 has preferably a flat rectangular bottom-side 20, while the upper side 21, is cylindrically shaped, as shown in Fig. 5. This construction makes it possible to place the invention on a dressing table in an upright position. Said bar has between the projections 11, a shallow recess 17, which permits the movements of the hooks 13, when the case is opened or closed.

To keep this protecting case securely in the pocket, I provide said pocket with two loops or straps 18, which may be slid over the ends of said bar to hold the same.

It is obvious that the present invention is not limited to any particular form of construction, and that it may be made of any suitable material, although I prefer to make the case parts of a light metal and the foundation bar of a metal somewhat heavier. Moreover it is not indispensable that all features of the invention be used conjointly as they may be advantageously employed in various combinations and sub-combinations.

Having thus fully described my invention, I claim as new and desire to secure by Letters Patent:

1. The combination with a pocket having loops or straps formed therein, of a bar over the ends of which said loops are engaged, projections on said bar, a pair of pins secured in said projections, a pair of half-circular supplementary case-parts pivoted on said pins, hooks formed with said case-parts, a coiled spring secured between said hooks for keeping said case-parts closed, said case-parts adapted to encircle a watch

and provided with supplementary half-circular openings for allowing an inspection of the watch hands therethrough, and having their front faces graduated corresponding to the watch dial, and means on the upper end of each of said case-parts to effect a rotation of said parts about their lower pivot points for permitting the removal of the watch.

2. The combination with a pocket having loops or straps formed therein, of a bar of substantially semi-circular cross-section over the ends of which said loops are engaged, projections on said bar in approximately the middle thereof, a pair of cross-pins secured with their ends in said projections, a pair of half-circular case-parts supplementing each other, pivoted at their lower ends to said cross-pins, hooks formed with said case-parts at their lower ends, a

coiled spring detachably secured between 20 said hooks for keeping the two case-parts closed about a watch and adapted to encircle the same, said case-parts provided with half circular openings in approximately their center supplementing each other 25 and allowing an inspection of the watch hands, said case-parts having their front faces graduated to correspond to the graduations of the watch dial, and projections or knobs at the top of each of said case-parts 30 to allow a rotation of the same about their lower pivot points for permitting the removal of the watch from the casing formed by said case-parts.

In testimony whereof, I have hereunto set 35 my hand.

RICHARD REMMLER.
